CORNER CABINET

Alfred Rabb, Jr., 422 Clermont Drive, Brooklyn, N.Y.

Filed Dec. 13, 1960, Ser. No. 63,210

Term of patent 14 years

(Cl. D33—19)

FIGURE 1 is a front perspective view of a corner cabinet showing my design with two of the drawers thereof and the terminal door members in partially open position;

The back of the article is conventionally plain.

I claim:

The ornamental design for a corner cabinet as shown and described.
